SHOE MANUFACTURE

Filed Nov. 20, 1937

FIG. 1.

FIG. 2.

Inventor

David I. Haskell,

By J. Richard Paris

Attorney

UNITED STATES PATENT OFFICE

2,185,993

SHOE MANUFACTURE

David I. Haskell, Augusta, Maine

Application November 28, 1937, Serial No. 175,717

8 Claims. (CL. 12—142)

The present invention relates generally to shoes for men, women, or children and is more particularly directed to an inner sole for such shoes and to a method of manufacturing shoes, the object being to enhance the flexibility of the shoe.

Considerable discomfort to the wearer of the shoe flows from the relative stiffness of the ball and toe portion of the sole of the shoe. This stiffness flows in large part from the inflexibility of the inner sole to the shoe and from the fact that, as the sole of the shoe is flexed, the inner sole, being on the inside of the curve, is subjected to great crowding. In many instances it has been observed that the inner soles of the shoes under conditions of wear buckle and corrugate, thereby rendering the shoe quite uncomfortable after only a short time of wear. It is the object of the present invention to eliminate this tendency of the inner sole to corrugate and buckle and thereby to greatly enhance the flexibility of the entire sole of the shoe, and thereby increase the comfort of the shoe and enhance its life.

The present invention accomplishes this end by so constructing a shoe that parts of the inner sole are permitted to have relative movement to each other during flexing and unflexing. To accomplish the end of the present invention such relative movement need be so slight that it is not at all felt by the foot.

In the present embodiment of the invention such relative movement of the parts of the inner sole is obtained by removing from the inner sole, which may be of any desired and suitable material that is commonly employed in inner soles, a relatively small transverse portion thereof and substituting or inserting in lieu thereof a piece of elastic material such as rubber, elastic webbing, or any fabric which comprises rubber strands or threads to render the same elastic, or similar materials.

In the present embodiment of the invention the method of manufacture of the shoe is modified in that the inner sole is applied to the last in a strained or stretched state or condition. This operation is followed by the normal operations in the manufacture of a shoe such as the lasting of the upper and the applying of the filler and outer sole. The result is that in the completed shoe, while the outer edge of the inner sole is firmly attached to the upper and the outer sole by any one of the customary processes employed in the manufacture of shoes, such as tacking, stitching, or cementing, the elastic insert and the parts adjacent to it remain under tension. When the

shoe is flexed, the tension in the elastic member serves to draw the adjacent parts toward each other and thereby prevent buckling of the inner sole, this also serving to assist in flexing the inner sole, thereby rendering the entire shoe more flexible.

In the drawing:

Fig. 1 is a plan view of the inner sole embodying the present invention; and

Fig. 2 is a section thereof on the line 2—2 10 of Fig. 1.

The inner sole 10 consists of any suitable material such as leather or any of the materials or fabrics that are now commonly employed in the manufacture of such inner soles. It comprises 15 the toe portion 11 and the main body portion 12 with the portion 13 of elastic material such as rubber or any other elastic fabric inserted between the portions 11 and 12. The edges of the three parts of the present inner sole are skived as 20 shown at 14 and 15 in Fig. 2. The portion 13 is preferably of the same thickness as the remainder of the inner sole and the edges thereof are skived along the same angle as the adjacent portions 11 and 12. The portion 13 is firmly attached 25 to the portions 11 and 12 either by paste, glue, or any suitable adhesive 16 with or without the aid of heat and pressure, or the same may be attached by lines of stitching 17, or both of these means of attachment may be used simultaneously.

The inner sole 10 as shown in full lines in Fig. 1 is slightly shorter in over-all length than the normal inner sole employed for the same size and style of shoe. In use the present inner sole when 35 applied to the last is first tacked onto the last at 18. The inner sole is then stretched so that it takes on the shape and size shown by dotted lines 19, and the inner sole is then again tacked to the last by tack 23. The operator in the factory 40 is obviously guided by the size and shape of the last bottom in the stretching operation. The inner sole is further tacked to the last bottom by tack 28 at the heel and sometimes also by tack 21 in the shank of the last. The all-over stretch 45 to which the inner sole is subjected need not be more than one-eighth or three-sixteenths of an inch. Dotted line 22 indicates the stretch of the elastic portion 13. The elastic portion 13 need not be more than a half or three-quarters of an 50 inch in its maximum width. On its narrow face, it should be about one-fourth or three-eighths of an inch and about twice that width on its wider face. The elastic portion 13 should preferably be inserted in the forepart of the ball portion of the

inner sole substantially as shown in the drawing.

The manufacture of the shoe is then proceeded with in the customary way.

5 It will now be understood that when the shoe is completed the tensioned elastic insert 13 which also subjects the adjacent portion 22, namely the adjacent ball portions of the inner sole, to tension, tends to draw the same forward. In use the 10 flexing of the shoe starts from the end of the shank or the rear part of the ball portion of the shoe and proceeds forward. This actually having the tendency to push the ball portion of the inner sole forward which in the present case is 15 highly assisted by the tension of the elastic insert which draws the ball portion of the inner sole forward and thereby prevents any buckling of that portion or any portion of the inner sole, and, of course, also greatly assists in flexing the same 20 by eliminating the resistance to such flexing.

One method of manufacturing the present innersole is as follows. The innersole is dinked by the normal die designed for the specific style and size of last out of a strip of the ordinary material employed in the manufacture of innersoles. This innersole will then have the size and shape indicated by the dotted line in Fig. 1 of the drawing. A portion is then removed from the fore-part of the innersole. This portion should preferably be disposed as shown in the forward portion of the ball portion of the innersole or could, perhaps best be described as disposed between the toe portion and the ball portion of the innersole. The two parts of the innersole are then joined by a strip of elastic material which is narrower in width than the removed portion. The difference need not be more than an eighth of an inch. The edges, of course, may be skived as shown in the drawing.

40 Another method of manufacturing the present innersole comprises the step of preparing a composite sheet or web of material which has two spaced strips of ordinary innersole material such as leather or fabric or any suitable fibrous material or the like which are commonly employed and generally desirable for innersoles, and an intermediate strip of elastic material such as rubber or a fabric comprising rubber strands or yarns. The adjacent edges are preferably skived and cemented together by methods well known in the art. Such sheets or webs of material may then be employed for die cutting or dinking out any desired number of innersoles embodying the present invention. The dies employed in the dinking operation are carefully designed and constructed so that the cutting edge has the contour indicated in full lines in Fig. 1 herein, which contour it should be noted does not correspond to the shape or contour of the last. 45 By virtue, however, of the elastic portion the innersole may subsequently, as will be understood from earlier portions of the present specification, be stretched to the shape and contour of the

bottom of the last, or as shown by the dotted lines in Fig. 1.

Having thus described my invention, I claim:

1. The method of making shoes which comprises supplying an innersole shorter than the last and having a transverse portion of elastic material disposed in the zone between its ball and toe portions and assembling said innersole on a last comprising the steps of tacking the toe of said innersole on the last and in registry with the toe of the last, stretching said innersole to the length of the last and tacking the same to the last.

15 2. The method of making shoes which comprises supplying an innersole shorter than the last and having a transverse portion of elastic material disposed in the zone between its ball and toe portions and assembling said innersole on a last comprising the steps of tacking one part of said innersole on the last and in registry with the last, stretching said innersole to the length of the last and tacking the same to the last.

20 3. The method of making shoes which comprises supplying an innersole shorter than the last and having a portion of elastic material and assembling said innersole on a last comprising the steps of tacking one part of said innersole on the last, stretching said innersole to the length of the last and tacking the other part to the last.

25 4. The method of making shoes which comprises supplying a short innersole having an elastic portion, affixing the same to a last bottom and concurrently tensioning and stretching the innersole to the length of the last, and thereafter lasting the upper and securing it to the innersole.

30 5. The method of making shoes which comprises supplying a short and elastic innersole, affixing the same to a last bottom and concurrently tensioning and stretching the same to the length of the last and thereafter lasting the upper and securing it to the innersole.

35 6. In a shoe, an innersole having a main body portion and a toe portion, each made of non-elastic material, and a part of elastic material interposed between said portions, said elastic material being in a stretched condition.

40 7. The method of making shoes which comprises supplying an innersole shorter than the last and having in its forepart a portion of expandable material, and assembling said innersole on a last, comprising the steps of tacking one part of said innersole on the last, expanding said innersole to the length of the last, and tacking the other part to the last.

45 8. The method of making shoes which comprises supplying a short expandable and contractible innersole, affixing the same to the last bottom and concurrently tensioning and stretching the same to the length of the last, and thereafter lasting the upper and securing it to the innersole.

DAVID I. HASKELL.
